COMB MOUNTING MEANS FOR HAIR CLIPPERS

Adelmo Giorgi, Highwood, Ill.

Application September 1, 1948, Serial No. 47,165

13 Claims. (Cl. 30—201)

1

This invention relates generally to hair clippers of either the mechanically operated or the manually operated type. In particular, the improvements contemplated herein have special reference to a unitary assembly for mounting a comb in coactive relationship with the operating head or distal portion of a hair clipper. Such an assembly is constructed and arranged in a manner which permits tilting movement of the comb at the will of the operator for selectively predetermining the length of the cut made by the hair clipper. Also the length of the cut may be progressively increased or decreased for producing the desired style of the finished haircut.

Furthermore, this unitary assembly is capable of adjusting the comb to a desired position with respect to the clipper guard and cutter members, and then maintained in such selected relationship to said clipper members for cutting hair at a uniform length throughout the major portion of a person's scalp, as for example when a so-called "crew" or "butch" style of haircut is desired. Due to the selective characteristics of the present arrangement and its easy manipulation, the operation of haircutting is materially simplified so that such operation may be readily performed by persons unskilled in the tonsorial art. Hence it is apparent that a skilled barber by the use of the present improvements is able to perform a job of haircutting in a much shorter time than with the usual comb and shears, and will be able to do this work without the use of a separate comb which requires both hands for proper manipulation. It will thus be seen that the operator does not have to wield a separate comb and therefore will have one hand free at all times while cutting a customer's hair.

Other objects, aims and advantages of the present arrangement will be apparent to persons skilled in the art, after the construction and operation of the improvements contemplated herein are understood from the within description. It is intended to accomplish the various objects hereof, and to practice the invention, in substantially the manner hereinafter fully described, and as more particularly pointed out in the appended claims.

Reference is now made to the accompanying drawings which form a part of this specification.

In the drawings:

Fig. 1 is a side edge elevation showing a clipper head with the present comb mounting assembly thereon;

2

Fig. 2 is a sectional plan of the under side of the structure shown in Fig. 1 looking at the same along the plane of line 2—2 on Fig. 1;

Fig. 3 is a longitudinal sectional view taken along the plane of line 3—3 in Fig. 2 and showing the relative position of the parts when the restraining means is released;

Fig. 4 is a view, similar to Fig. 3, showing the parts held in position by the restraining means; and

Fig. 5 is a fragmentary front elevational view taken from the left of Fig. 4.

The drawings are to be understood as being more or less of a diagrammatic character for the purpose of disclosing the type or preferred form of the invention contemplated herein, and in the drawings like reference characters identify the same parts in the different views.

The clipper actuating mechanism and its 20 motor, which are housed within a casing (not shown), may be of any of the well-known constructions generally employed for vibrating the cutter 10 across a toothed guard 11 which has parallel flat bearing ribs 12 and 13 to receive 25 the sliding cutter and also has well-defined parallel side edges 14 which project beyond the corresponding sides or ends of the cutter. These projecting side edges are utilized in the present arrangement for supporting the improved comb 30 assembly contemplated herein.

The comb assembly comprises a mounting plate 15 having reinforcing ribs 16 extending longitudinally thereof, and at its ends said plate is provided with upwardly outwardly flared lips 17 which are somewhat yieldable to permit the mounting or attaching plate to be readily snapped in position over the end edges 14 of the guard 11. Spaced from the mounting plate 15 there is a carrier means for the comb 18. These carrier means may comprise a flat plate 19 that is spaced outwardly away from the mounting plate 15 and is preferably arranged at an angle to the plane thereof, so that these plates converge in an outwardly direction toward the distal portion of the cutter assembly as clearly shown in the drawings. The end edges of the holder plate 19 are flanged outwardly as at 20 to embrace the side or end edges 18a of the comb. This arrangement permits the comb to be slidingly adjusted in the holder in directions toward and away from the guard of the clipper.

For the purpose of permitting yielding or tilting movement of the comb assembly in a plurality of directions with respect to the clipper head, the holder assembly is connected to the

attaching plate 15 by relatively narrow spring-like members 21 of S-shape. For the purpose of providing a unitary assembly of the attaching plate and comb holder plate the spring portions 21 are formed from the same piece of metal as said plates. The sliding or adjusting movement of the comb on the holder assembly may be arrested in different positions by providing a plurality of ridges 22 on the back portion of the comb, as seen clearly in Fig. 2, said ribs being arranged parallel to each other and being adapted to be engaged by small ears 23 formed by turning down flanges on the central region of the mounting plate 19 so that said ears will engage between two adjacent ribs. A handle portion 24 projects centrally from the rear portion of holder plate 19. Since the unitary assembly is of spring metal the holder plate 19 may be warped slightly in an upward direction by the operator raising or moving the handle portion 24 in a direction toward the clipper head. This will withdraw the ears 23 from the ribs and the comb may then be slid to a desired position with respect to the clipper head where it may again be locked in place.

It is desirable under certain conditions to latch the comb assembly in desired relationship to the clipper head for the purpose of operating on the customer's head to cut what is commonly known as a "butch" or "crew" haircut. This is accomplished by providing a swinging lever 25 which is pivotally mounted upon a rivet 26 on the underneath portion of the attaching plate 15 so that this lever may be swung to different positions on its fulcrum 26. As seen in the drawings the end of the lever 25 nearest the distal end of the clipper is of L-shape with the flange portion 27 in a position so that it will engage the comb 18 when the lever is in the positions shown in the drawings, particularly Figs. 1, 2, 4 and 5.

Referring to Fig. 5 it will be noted that the flange 27 of the pivoting lever engages the comb between the teeth thereof when in the position shown. By swinging the lever to the right or left the flange portion 27 will be engaged between the other teeth of the comb and in such positions there is a change of angularity between the planes of the comb 18 and the clipper guard 14. When not in use the lever 27 is swung to a position nearly parallel with the attaching plate 15 in the manner shown in dotted lines on Fig. 2.

From the foregoing it is apparent the assembly unit may readily be fabricated from a flat piece of metal having a central portion removed to provide the two elongated end regions defining the mounting plate 15 and the comb carrier plate 19, which end regions are connected by narrow spring-like strips which are later formed in an S-shaped bend to define the springs 21.

In operation it will be understood the comb is placed against the scalp and moved in the proper direction for cutting the hair with the clipper head. During the cutting operation the relative movement between the clipper and comb permits the operator to tilt the clipper to graduate the length of the cut progressively in the direction in which the assembly is moved. The springs 21 permit this tilting and also allow the operator to cant the clipper with respect to the comb by pressing more firmly towards one side. This is useful when clipping the hair around or adjacent the ears. When a uniform cut is desired over the entire scalp the operator may swing the lever 25 on its pivot so that the lip or lateral portion 27 will engage in the spaces between the

comb teeth as shown in Fig. 5. This prevents movement of the clipper toward the comb and the cut made by the clipper will be uniform so long as the comb is moved flat against the scalp.

While this invention has been described in its typical or preferred embodiment it will be apparent to persons skilled in the art after understanding the construction and operation of this assembly that changes and modifications may be made therein, without departing from the spirit or scope thereof. It is aimed in the appended claims to cover all such changes and modifications.

What is claimed is:

1. An assembly for mounting a comb on a hair clipper comprising attaching means adapted to be mounted on the head of the clipper; comb holder means arranged in a plane spaced from said attaching means; a comb mounted on said holder means and adapted for adjustable sliding movement thereon; spring means connecting said holder means to said attaching means for yieldable bodily movement of said holder means in a plurality of directions with respect to said attaching means; coacting latching means on said comb and said holder means adapted to releasably retain said comb in any of the aforesaid adjusted positions with respect to said holder means; a lever pivotally carried by said attaching means for swinging movement with respect thereto; and a lateral member on said lever projecting towards and adapted to be engaged with said comb to restrain said holder means and comb against said yieldable bodily movement with respect to said attaching means.

2. An assembly for mounting a comb on a hair clipper comprising attaching means adapted to be mounted on the head of the clipper; a comb arranged in a plane spaced from said attaching means; means yieldably mounting said comb for bodily movement in a plurality of directions with respect to said attaching means; said comb being slidably adjustable on said mounting means; lugs on said mounting means coacting with ribs on the back of said comb adapted to releasably retain said comb in any of the aforesaid adjusted positions; and means operative to restrain said comb against said yieldable bodily movement with respect to said attaching means.

3. An assembly for mounting a comb on a hair clipper comprising a one-piece metal sheet having reversely bent portions intermediate its ends to provide springs joining the end regions, and the end portions defining respectively an attaching plate cooperating with the clipper guard and a comb receiving plate arranged in a plane spaced from said attaching plate; a comb mounted for bodily sliding movement on the comb receiving plate; coacting latching means on said comb and said receiving plate adapted to releasably retain said comb in any of the aforesaid adjusted positions with respect to said receiving plate; and lever means operative between said attaching plate and said comb to restrain said comb against said yieldable bodily movement with respect to said attaching plate.

4. An assembly for mounting a comb on a hair clipper comprising attaching means adapted to be mounted on the head of the clipper; comb holder means arranged in a plane spaced from said attaching means; a comb mounted on said holder means and adapted for adjustable sliding movement thereon; spring means connecting said holder means to said attaching means for yieldable bodily movement of said holder means in a

plurality of directions with respect to said attaching means; coacting latching means on said comb and said holder means adapted to releasably retain said comb in any of the aforesaid adjusted positions with respect to said holder means; and means operative to restrain said holder means and comb against said yieldable bodily movement with respect to said attaching means.

5. An assembly for mounting a comb on a hair clipper comprising an attaching plate adapted to be mounted on the clipper head; comb holding means carried by said attaching plate in spaced relation thereto; S-shape spring means connecting said holder to said attaching plate adapting said holder for tilting movement in a plurality of directions with respect to said attaching plate and independently thereof; a comb mounted on said holder for adjustable movement thereon; ribs on the back of said comb extending transverse to the planes of the comb teeth; lateral lug means on said holder for engagement with said ribs thereby to positively lock said comb in any of its adjusted positions with respect to said holder; and release means on said holder for disengaging said lug means from said ribs.

6. An assembly for mounting a comb on a hair clipper comprising an attaching plate supported on the clipper head; a comb holder carried by said attaching plate in spaced relation thereto; reversely bent spring means connecting said holder to said attaching plate adapting said holder for tilting movement in a plurality of directions with respect to said attaching plate and independently thereof; a comb mounted on said holder for adjustable movement thereon; ribs on the back of said comb extending transverse to the planes of the comb teeth; lugs on said holder for engagement with said ribs thereby to positively lock said comb in any of its adjusted positions with respect to said holder; release means on said holder for disengaging said lug means from said ribs; and an L-shape lever pivoted on said comb holder for swinging movement thereon, the lateral member of said L-shape lever being effective in a plurality of positions to maintain said comb and holder against tilting movement with respect to said attaching plate and clipper head.

7. A comb supporting assembly for hair clippers comprising a sheet metal plate defining spaced first and second end sections, said sections being connected by yieldable spring means of reversely bent form for effecting relative movement between said sections the one with respect to each other; said first section being adapted for attachment to the distal portion of a hair clipper; a comb adjustably carried by said second section in a plane which is normally oblique to the plane of said first section, said comb being adapted for sliding movement on said second section in directions toward and away from said hair clipper distal portion; said spring means adapting said comb for yielding movement to either side of said normal oblique plane thereby to selectively vary the distance between the tips of the comb teeth and the distal end of the clipper during clipping operations; means on said assembly for releasably maintaining said comb in any of said adjustable positions; and means for resisting relative yieldable movement between said first and second sections of said assembly.

8. A comb supporting assembly for hair clippers comprising a sheet metal plate defining spaced first and second end sections; narrow spring strips connecting end regions of said sec-

tions for yielding relative movement the one with respect to the other; said first section having thereon means adapting assembly for attachment to the distal portion of a hair clipper; comb receiving means on said second section; a comb carried by said means, said comb being in a plane that is normally oblique to the plane of said first section and being adjustable in directions towards and from the plane of the distal end of the hair clipper; recesses on said comb arranged in planes transverse to the planes of the comb teeth; lug means on said second section between said comb receiving means and adapted for engagement with said recesses to releasably maintain said comb in any of said adjustable positions; an arm projecting rearwardly from said second section, said arm being manually operable for distorting said second section thereby to release said lug means from a recess whereby sliding adjustment of said comb is effected; and pivoted lever means carried by said first section and operative to a plurality of positions for arresting relative yieldable movement between said first and second sections of said assembly in said positions.

25. 9. A comb supporting assembly for hair clippers comprising a sheet metal plate shaped to define spaced first and second end sections, said sections being connected by yieldable spring means of reversely bent form for effecting relative movement between said first and second sections with respect to each other; said first section having means thereon adapting assembly for attachment to the distal portion of a hair clipper; a comb carried by said second section in a plane oblique to the plane of said first section; means on said second section for receiving said comb and adapting said comb for slidable adjustable movement in directions toward and away from said hair clipper portion; coacting means on said comb and said second section for releasably maintaining said comb in any of said adjustable positions; and means for arresting relative yieldable movement between said first and second sections of said assembly.

45. 10. A comb assembly for hair clippers comprising an attaching member adapted to be secured to the clipper head; a comb arranged in spaced relation to said attaching means; a holder member yieldably connected to said attaching member for supporting said comb in the aforesaid spaced relation to said attaching member and adapting said comb for yieldable tilting movement in a variety of directions with respect to said attaching member; a manually operable lever mounted for pivotal movement on one of said members; and means on said lever operative to restrain said comb against said yieldable movement with respect to said attaching member.

60. 11. A comb assembly for hair clippers as defined in claim 10, wherein the holder member comprises a supporting plate on which the comb has sliding movement; and latch means releasably maintaining the comb against said sliding movement on the supporting plate.

65. 12. A comb assembly for a hair clipper head comprising an attaching plate coactively associated with said clipper head; a supporting plate for a comb; said plates being arranged in spaced relation to each other; a comb received on said supporting plate; spring arm means connecting said plates, said spring arm means yieldably fulcruming said supporting plate and said comb for tilting movement with respect to said attaching plate and the clipper head; and manually operable means selectively movable to a plurality

of positions for predetermining the extent of tilting movement of said supporting plate and the comb carried thereby.

13. A comb assembly for hair clippers as defined in claim 12, wherein the comb is slidably movable on the supporting plate; and releasable latching means operable to restrain the comb against sliding movement on the supporting plate.
